UNITED STATES PATENT OFFICE

HARRY BORTON, OF BELOIT, OHIO

DROP FORGE DIE ADJUSTER

Application filed January 30, 1931. Serial No. 512,408.

This invention appertains to new and useful improvements for adjusting the dies of drop forge hammers in a quick and efficient manner.

5 An important object of the invention is to provide means for adjusting dies for drop forge hammers in an accurate and time-saving manner.

Other important objects and advantages 10 of the invention will become apparent to the reader of the following specification and claims.

In the drawings:—

Figure 1 represents a front elevational 15 view of the hammer with the tie secured thereto.

Fig. 2 represents a vertical sectional view through the die taken substantially on the line 2—2 of Fig. 3.

20 Fig. 3 represents a top plan view of the hammer and die.

Fig. 4 represents a sectional view taken substantially on line 4—4 of Fig. 1.

Fig. 5 represents a side elevational view 25 of the hammer and die.

Fig. 6 represents a vertical sectional view taken substantially on the line 6—6 of Fig. 2.

Fig. 7 represents a vertical sectional view 30 also taken substantially on the line 2—2 of Fig. 3, and showing the die after having been adjusted (see Fig. 2) in conjunction with the service.

Fig. 8 represents a perspective view of one 35 of the wedge members.

Referring to the drawings wherein like numerals designate like parts, it can be seen that numeral 5 represents the hammer of the drop forge machine. In this block 5 is a vertically disposed dove-tail block 6 within 40 which the conformingly shaped tongue 7 on the die 8 is slidable. The width of the tongue 7 is substantially less than the width of the groove 6 so as to accommodate the elongated tapering key 9.

45 As is shown in Fig. 2, the hammer 5 is

shown provided with a pocket 10, the side walls 11 and 12 of which converge toward the groove 6 where the pocket can communicate with the groove. Projecting into this pocket 10 from the die 8 is the outwardly tapering 50 dowel 13, which is anchored in the die 8 in any suitable manner as at 14.

As is clearly shown in Fig. 2, a wedge member 15 is located between each side wall 11 and 12, and the corresponding side of the 55 dowel 13. Extending from these wedges 15 are the threaded shanks 16 provided with reduced and squared ends 17. The outer ends of the stems 16 project beyond one side of the hammer 5 and are equipped with nuts 18 60 which can be urged against the said side of the hammer to secure the said stems against self-adjusting.

It can now be seen, that without removing the key 9, the wedges 15 can be fed inwardly 65 or outwardly so as to exert pressure against the dowel 13 in one direction or the other to properly adjust the die to the desired position.

Obviously, for major adjustments and replacements, the key 9 is removed, and in the 70 case of micromic adjustments of this character, the wedges 15 will permit more accurate adjusting.

While the foregoing specification sets forth the invention in specific terms, it is to be understood that numerous changes in the shape, size, and materials may be resorted to without departing from the spirit and scope of the invention as claimed hereinafter.

Having thus described my invention, what 80 I claim as new is:—

1. In combination, a hammer, a die, a tongue and groove connection between the die and the hammer, a tapering projection on the die, a pair of wedge members engageable 85 against opposite sides of the projection, and screw means whereby the wedge members may be forced against or retracted with respect to the projection.

2. In combination, a hammer, a die body, 90

said body being slidable on the hammer and provided with a lateral projection, and a pair of adjustable wedge members on the hammer for engagement against opposite sides of the said projection.

5 3. In combination, a hammer provided with a pair of shoulders defining a groove, a die body slidable in the groove and between the shoulders, a lateral projection at one side of the body, a pair of adjustable wedges on the hammer for engaging opposite sides of the projection, and an elongated wedge for interposition between one of the shoulders and the adjacent side of the die body.

10 15 In testimony whereof I affix my signature.
HARRY BORTON.
